UNITED STATES PATENT OFFICE.

JAMES F. McELROY, OF ALBANY, NEW YORK, ASSIGNOR TO CONSOLIDATED CAR HEATING COMPANY, OF ALBANY, NEW YORK, A CORPORATION OF WEST VIRGINIA.

TRAIN-PIPE TERMINAL FOR CAR-HEATING SYSTEMS.

SPECIFICATION forming part of Letters Patent No. 758,269, dated April 26, 1904.

Application filed February 4, 1904. Serial No. 191,934. (No model.)

To all whom it may concern:

Be it known that I, JAMES F. McELROY, a citizen of the United States, residing at Albany, county of Albany, and State of New York, have invented a certain new and useful Improvement in Train-Pipe Terminals for Car-Heating Systems, of which the following specification and accompanying drawings disclose as an illustration one embodiment thereof, of which I now regard as the best out of the various forms in which the principles of the invention may be applied.

In the drawings, Figure 1 is a plan, and Fig. 2 is a side elevation, of my device; and Fig. 3 is a section through the terminal.

The particular object of my invention is to provide a train-pipe terminal containing an end valve capable of operation from outside of the car and also adapted to coöperate with the train-pipe on the one hand and the hose on the other hand, so as to combine in the one terminal device a coupling and a valve that will also serve as a train-pipe terminal to which the hose may be directly connected. One branch of the device is turned downward to engage with the hose and the other branch lies at an angle to the longitudinal line of the car to coöperate with an angular portion of the train-pipe, while there is also in the device a valve with a stem projecting laterally from the longitudinal line of the car and at a different angle from either of the two coupling branches of the valve.

The device is also one that gives but a small resistance to the flow of the steam from the train-pipe of one car to that of the next one and is simple and cheap to construct.

Referring to the drawings, A, Fig. 1, represents a train-pipe on a car B, located at one side of the car and designed to be connected, through the hose-pipes C C', to a corresponding section of train-pipe A' on car D. The train-pipe is bent at its outer end, so as to have a terminal section that diverges diagonally at an easy angle from the longitudinal line of the car toward the center of the car and slightly downward, as shown in Fig. 2, so as to bring it nearer to the center of the car in a position to connect with the hose-pipe C.

E is the train-pipe terminal, located at the end of the train-pipe and provided with a valve having its axis at right angles to the longitudinal line of the car, and forming an extension of the valve-stem is an operating handle F. The terminal is provided with two coupling branches: First, the branch a, which departs from the body of the terminal at an angle about midway between the longitudinal line of the car and the axis of the valve. This branch is also turned slightly upward, as seen in Fig. 2, to form a lineal continuation of the bent end of train-pipe A. Second, there is a branch a', which, as seen in Fig. 2, is turned down nearly at right angles to communicate with the hose C. The former branch is provided with a permanent connection to the train-pipe and the latter branch has the usual removable connection with the hose. By this arrangement I produce a single article in which is combined an end valve having its stem substantially at right angles to the longitudinal line of the car, so as to be operated directly by the handle F, projecting outward in line with the valve-stem, and also a coupler communicating on one side with the train-pipe A and on the other with the hose-pipe C, the whole constituting a terminal for the train-pipe suitable for the ready connection thereto or disconnection therefrom of the hose. Moreover, as appears in Fig. 3, the route of the passage through the terminal involves but slight and easy angles presenting little obstruction to the flow of the steam-current from car to car and through the train.

What I claim as new, and desire to secure by Letters Patent, is—

1. A train-pipe terminal for a car-heating system comprising, first, an end valve having its axis at right angles to the car and, second, two coupling branches, one placed at an angle between the axis of the valve and the longitudinal line of the car and the other turned downward at approximately a right angle to the axis of the valve, the former branch being adapted to connect with a diagonal end section of the train-pipe and the latter branch being adapted to communicate with a hose-pipe.

2. A train-pipe terminal for a car-heating system comprising, first, an end valve having

its axis at right angles to the line of the car with an operating-handle F projecting in line with the axis of the valve and, second, two branches one a coupling branch a at an intermediate angle between the axis of the valve and the longitudinal line of the car and the other a branch a' turned downward and provided with a hose-coupling.

3. In a car-heating system the combination 10 with a train-pipe lying along one side of the center of the car but turned inward toward the center of the car at its end of a terminal E comprising a combined valve and coupler having the diverging branches a and a' communicating respectively with the train-pipe and a coupling-hose, and provided also with an operating-handle F extending laterally beyond the edge of the car-platform.

4. A train-pipe terminal for a car-heating 20 system, comprising a combined end valve and coupler having two branches, one a diagonal branch adapted to communicate with the train-pipe and the other a downward branch adapted to communicate with the hose, and having also

a projecting valve-handle for operating the 25 valve from the side of the car.

5. In a car-heating system, the combination with a train-pipe lying along one side of the center of a car but turned inwardly so as to terminate near the center of the car, a terminal 30 for said train-pipe comprising a combined end valve and coupler having two diverging branches, one communicating with the train-pipe and the other provided with a hose-coupling, a hose communicating at its inner end 35 with the latter branch of the said terminal and at its outer end provided with a coupler adapted to connect with a similar coupler on the corresponding hose of an adjacent car, and an operating-handle for the end valve extending 40 therefrom toward the edge of the car-platform.

In witness whereof I have hereunto set my hand before two subscribing witnesses this 19th day of January, 1904.

JAMES F. McELROY
